CLAIM

The ornamental design for a seat, as shown and described.

DESCRIPTION

FIG. 1 is a perspective view of a seat showing my new design;

FIG. 2 is a front elevational view thereof;

FIG. 3 is a top plan view thereof;

FIG. 4 is a right side view thereof, the opposite side being a mirror image of the side shown;

FIG. 5 is a perspective view of a second embodiment thereof which differs only in length from the first embodiment; and,

FIG. 6 is a front elevational view of a third embodiment thereof which differs only in length from the first embodiment.

The rear view is not part of the claimed design. The side not shown in FIGS. 5 and 6 is a mirror image of that shown in FIG. 4.
